UNITED STATES PATENT OFFICE.

JAY G. HUNTER, OF SABULA, IOWA.

CONDENSER.

Application filed July 6, 1920, Serial No. 394,242. Renewed January 13, 1923.

To all whom it may concern:

Be it known that I, JAY G. HUNTER, a citizen of the United States, residing at Sabula, in the county of Jackson and State 5 of Iowa, have invented certain new and useful Improvements in Condensers, of which the following is a description.

My invention belongs to that general class of devices known as condensers, and particularly a condenser for use in connection with refrigerating systems. The invention has among its objects the production of a device of the kind described that is simple, convenient, compact, durable, efficient and 15 satisfactory for use wherever found applicable. It has among its further objects the production of a device of the kind described which consists of a minimum of parts and which is constructed with such simplicity 20 that the same will not easily get out of order or become inoperative. Many other objects and advantages will be obvious to those skilled in the art from the disclosure herein given.

25 To this end my invention consists in the novel construction, arrangement and combination of parts herein shown and described, and more particularly pointed out in the claims.

30 In the drawings, wherein like reference characters indicate like or corresponding parts,

Fig. 1 is a sectional view through one form of my device;

35 Fig. 2 is a cross sectional view taken substantially on line 2—2 of Fig. 1;

Fig. 3 is a sectional view similar to Fig. 1 of a slightly modified construction; and

40 Fig. 4 is a sectional view of another construction.

Referring to Figs. 1 and 2, it may be mentioned that I have not considered it necessary to illustrate the compressor, accumulator, coils and other parts of the refrigeration system used in connection with my condenser.

The condenser consists of an outer shell or casing 1, provided with a suitable bottom 2 and top or closure 3, the top being secured in place in any desired manner. Within the casing 1 is an inner wall 4 spaced therefrom to provide the space 5, the relative proportions of the casing 1 and inner part 4 being such as may be desired. I have shown the bottom formed as at 6 on the interior of the part 4 with an opening 7 at the

bottom, which is normally closed by a plate 8 secured in place by bolts 9 or their equivalents. When so constructed I preferably employ a packing ring 10 between the parts 60 1 so as to prevent leakage, the outer casing 1 with its top and bottom being so constructed that the gas cannot leak from the same when under pressure.

Arranged within the condenser, as shown 65 within the part 4 is a cooling coil 12, through which water or any equivalent cooling fluid may be circulated. The coil 12 is connected with an intake pipe 13 and with a discharge pipe 14. Connected with the condenser, as 70 shown extending through the cover plate 3, is an intake pipe 15 which is connected with the compressor or the like, and through which the gas is admitted to the condenser. Pipe 15 is connected with the pipe 16, preferably 75 having an up-turned end 17 at the outlet of which is arranged a check valve 18 or the equivalent. I prefer to provide what might be termed a cage 19 about the end of the pipe, the same having discharge openings 20 through the walls thereof. The condenser is connected with the refrigerating system, as for example with accumulator, by means of a pipe 21 or its equivalent. In this connection it will be noted that the pipe 80 21 communicates with the space 5, the said pipe being arranged adjacent but a little above the bottom 2 of the condenser. A drain pipe 22 also communicates with the bottom of the space 5 so that the space may 85 be drained. A drain pipe 23 is also provided for the inner part 4, so that by means of the two drain pipes all of the liquid may 90 be drained from the condenser. An oil discharge pipe 24 is preferably arranged as 95 shown, as well as an outlet pipe 25, which is normally closed except at such times as it may be desired to pump the gas or cooling medium from the compressor.

The operation of the condenser may be 100 described as follows: Assuming that pipe 13 is connected with a source of water supply, pipe 15 with the compressor and pipe 21 to the accumulator, gas enters through pipe 15 from the compressor, passes through pipes 105 16 and 17, past the check valve 18 and thence is discharged through the opening 20 into the inner shell 4. However, the same is liquefied in the inner shell 4 and the level of the liquid gradually rises until it reaches 110 the top of the wall of the inner part 4 and overflows. As soon as the level reaches

above the openings 19 the liquefaction is more rapid as the gas is discharged into the liquid. Flowing over the top of walls 4 it accumulates in the space 5, and as the pressure increases and the system begins to operate, the same flows through pipe 21 to the accumulator or other part of the refrigerating system. From there it flows back to the compressor in the form of a gas and is again discharged through pipe 15 into the condenser.

In the construction shown in Fig. 3, 31 represents a tank or shell within which is arranged an inner tank 32. About the inner tank 32 is provided a coil 33 which is connected with pipe 34 connected with pipe 36 extending from the compressor. However, the check valve 35 is preferably provided so that the gas cannot flow back to the compressor after it has once passed the valve. The coil 33 is connected by means of pipe 37 with the interior or chamber 38 of the tank 32, which tank is provided with an outlet or discharge pipe 39 extending to the accumulator or other desired part of the refrigerating system. Tank 31 is provided with a water or cooling medium intake pipe 41 and discharge pipe 42, drain pipes 40 and 43 being preferably arranged substantially as shown.

In the construction shown in Fig. 4, 44 represents a tank, within which is arranged a coil 45 through which water or any equivalent cooling medium may be passed. The tank 44 is connected with another tank 46 by means of the pipe 47 or the equivalent. Tank 44 is connected by means of pipe 48 with the compressor or the like, 49 being a check valve and 53 a valve for controlling the passage of the gas to the tank 44. Tank 46 is provided with the discharge pipe 50 extending to the accumulator or other part of the refrigerating system. 54 is a valve arranged in pipe 50, and 51 and 52 are drain pipes from the tanks 44 and 46, it being understood that the same are provided with suitable valves.

The operation of the device shown in Fig. 3 is substantially as follows: The gas comes from the compressor, past check valve 35 and through pipe 34 into the coil 33, which is in the cooling water so that the gas readily condenses, passing through the coil and pipe 37 into the tank 32. Any uncondensed gas is immediately condensed in the chamber 38. The liquefied gas flows from chamber 38 through pipe 39 to the accumulator or into the system.

In the construction shown in Fig. 4, the gas passes through pipe 48 from the compressor into the tank 44, and is cooled by the coil 45. As the liquefied gas accumulates it reaches pipe 47 and flows into the tank 46, from which it is conducted to the accumulator or refrigerator by the pipe 50.

This construction is very similar to that shown in Fig. 1 except that two tanks are employed.

Having thus described my invention, it is obvious that various immaterial modifications may be made in the same without departing from the spirit of my invention; hence I do not wish to be understood as limiting myself to the exact construction, arrangement and combination of parts herein shown and described, or uses mentioned.

What I claim as new and desire to secure by Letters Patent is:

1. In a condenser of the kind described and in combination, a plurality of receptacles providing a plurality of chambers, one constituting substantially a cooling chamber and the other a chamber for the accumulation of condensed gas, means for conducting gas to be condensed into the cooling chamber, means for preventing the discharge of gas through said conducting means from said cooling chamber and means for conducting a cooling medium through the cooling chamber. 90

2. In a condenser of the kind described and in combination, a plurality of receptacles arranged one within the other and providing a plurality of associated chambers, one constituting substantially a cooling chamber and the other a chamber for the accumulation of condensed gas, means for conducting gas to be condensed into the cooling chamber, and means for conducting a cooling medium into the bottom of the cooling chamber. 100

3. In a condenser of the kind described and in combination, a plurality of receptacles arranged one within the other providing a plurality of chambers, one constituting substantially a cooling chamber and the other a chamber for the accumulation of condensed gas, means for conducting gas to be condensed to the bottom of the cooling chamber, said chambers being in communication with one another whereby the gas condensed may overflow into the accumulating chamber, and means for conducting the cooling medium through the cooling chamber. 110

4. In a condenser of the kind described, receptacles arranged one within the other, means for conducting a cooling fluid to the inner receptacle and therefrom, means for conducting a gas so that it may be liquefied in the inner receptacle, means for conducting the condensed gas overflowing from the inner receptacle into the outer receptacle from the outer receptacle, and means for controlling the direction of the flow of the gas through the receptacle. 120

5. A condenser of the kind described, comprising the combination of a receptacle provided with a removable top and bottom and having an extending part at the interior 130

- from the bottom extending to adjacent the cover, cooling means arranged within said extending part, an intake pipe projected through the cover to the interior of said extending part and adjacent the bottom of the receptacle and thence turned upwardly at its inner end, means for preventing the discharge of gas through said pipe from the receptacle, a distributing cage arranged at the end of said pipe, a discharge pipe arranged adjacent the bottom of the receptacle and communicating with the space between the outer walls and the walls of said projecting part, and drain pipes extending from the receptacle and communicating with the space between the walls and with the interior of the extending part.
6. In a device of the kind described and in combination, a receptacle having a spaced inner wall extending upwardly from the bottom of the receptacle, a closure detachably secured at the upper end of said receptacle, said inner wall extending to adjacent said closure but spaced therefrom, a coil arranged within the receptacle within the confines of the inner wall and provided with an intake pipe extending through the bottom of the receptacle and a discharge pipe extending through the top, an intake pipe projected downwardly through the cover to adjacent the bottom of the receptacle within the inner wall and having its inner end turned upwardly, provided with means at the end for distributing the gas admitted therethrough and with means for preventing the readmission of the gas to the pipe after its discharge into the receptacle, a discharge pipe for conducting the condensed gas dis-
- charged into the space between the two walls over the top of the inner wall, and means for draining the receptacle as desired.
7. In a device of the kind described, a condenser comprising a receptacle having a bottom and provided with a top detachably secured thereto, said casing provided with a part extending from the bottom and substantially constituting an inner receptacle, providing a cooling chamber, the space between the outer and inner walls of the receptacles substantially constituting a chamber for the accumulation of liquefied gas, a coil arranged within the cooling chamber and provided with an intake pipe and a discharge pipe connected therewith, said bottom of the receptacle provided with an opening therethrough and with a closure for said opening, one end of said coil connected to one of said pipes through said plate, a gas pipe depending from the detachable top into the inner receptacle and cooling chamber to adjacent the bottom thereof, the lower end of said pipe turned upwardly, means at the discharge end of said pipe for controlling the passage of gas through the pipe and preventing a back flow therein, means for conducting the accumulated condensed gas from the receptacle, and means for draining the receptacles as desired.
- In testimony whereof, I have hereunto signed my name in the presence of two subscribing witnesses.

JAY G. HUNTER.
